HEINRICH BERNHARD RÜDER, OF FRANKFORT-ON-THE-MAIN, GERMANY, ASSIGNOR TO
INTERNATIONAL PRECIPITATION COMPANY, OF LOS ANGELES, CALIFORNIA, A
CORPORATION OF CALIFORNIA

MEANS FOR HIGH TENSION INSULATION

Application filed June 17, 1930, Serial No. 461,831, and in Germany July 17, 1929.

This invention relates to the insulation of high tension electric conductors or other bodies to be maintained at high electric potential with respect to surrounding bodies, and the invention is directed particularly to means for heating high tension insulators.

It is in many cases necessary or advantageous to heat high tension insulators, in order to prevent short circuiting across the surface 10 of the insulators due to formation of conducting films of condensed liquid on the surface thereof or to prevent short circuiting through the body of the insulators in case of porous materials, such as clay, which are sometimes 15 used at certain temperatures, due to penetration of condensed liquid into the interior of such insulating material. The condensed liquid which must be thus guarded against may result from condensation of vapors from 20 the surrounding atmosphere or gaseous medium, for example, the condensation of moisture or water vapor from air or the condensation of condensable constituents from other gases surrounding the insulators.

25 For example, in electrical precipitation apparatus the gases to be treated are frequently at a temperature in excess of atmospheric temperature or in excess of the temperature at which the high tension insulating means of such apparatus would be maintained if no particular heating means were provided, and such gases also frequently contain water vapor or other vapors which tend to condense upon contact with bodies at lower 30 temperature than the gases. This invention is particularly intended and adapted for use in connection with the high tension insulating means of electrical precipitation apparatus, but may also be used in connection with 35 any high tension insulators where it is necessary to heat the same in order to prevent condensation or accumulation of conducting materials thereon.

In case the gases to be treated in an electrical precipitation apparatus, or otherwise brought into contact with high tension insulating means, contain combustible constituents, there is a still greater necessity for heating the insulators to prevent condensation of 45 conducting liquid thereon, for in such cases

short circuiting through the insulators or across the surfaces thereof may lead to serious fires or explosions.

Various means have heretofore been used or proposed for heating the insulators, such 55 means usually comprising means for passing a heating medium through, around or over the insulators, so as to heat them principally by conduction. These heating means, however, have the common disadvantage that the 60 heating means must be placed immediately on the surface of the insulator or in contact therewith, and it has been difficult to bring the heating apparatus in sufficiently close contact with the insulators to provide the 65 necessary heating, without causing short circuiting through the heat conducting walls of the heating apparatus itself. Another disadvantage of the heating means heretofore used is that the heating is rather localized, 70 and irregular on different parts of the insulator surface; and furthermore it is difficult to maintain the surfaces of the insulators at the desired temperature without having to heat the entire body of the insulators 75 to substantially the same temperature. Such heating means have, therefore, proved not only inefficient in some cases but also uneconomical.

The principal object of this invention is to 80 provide more efficient and economical means for heating high tension insulators without the introduction of any difficulties due to tendency to short circuiting through the heating apparatus. According to my invention 85 this object is accomplished by heating the insulators, and particularly the surfaces thereof, by radiation of heat onto such surfaces from heat radiating or reflecting means which are sufficiently remote from the 90 conductors to prevent short circuiting from the high tension conductors or bodies through the heating radiating means.

The invention comprises essentially the combination with a high tension insulator, 95 of means spaced from the insulator and adapted to radiate heat onto the surface of the insulator. The radiating means may comprise any suitable source of radiant heat, and preferably comprises a source of 100

radiant heat such as an electric heating coil or an incandescent lamp, and heat reflecting means so as to reflect heat from said source upon the surface of the insulators. In some cases, and particularly where it is desired to protect the heat reflecting surfaces or the source of heat from deposition of dust or foreign matter thereon, as in the case of the insulators in electrical precipitation apparatus which are exposed to gases containing suspended solid or liquid material, I prefer to mount the heat reflecting means and preferably the source of heat also in a chamber separated from the gases surrounding the insulator and provided with heat transmitting walls, such as windows of glass or other suitable material, in position between the heat radiating means and the insulator, so as to permit effective radiation of heat from said radiating means onto the insulators while preventing access of the gases and the suspended material contained therein to the heat radiating or reflecting means.

The accompanying drawings illustrate a simple embodiment of my invention, as applied to the insulators in an electrical precipitation apparatus, and referring to these drawings:

Fig. 1 is a vertical section of a portion of an electrical precipitation apparatus provided with high tension insulating means and with means for heating the high tension insulators according to this invention.

Fig. 2 is a section on line 2-2 in Fig. 1. A side wall of the precipitator chamber is indicated at 1 and the top wall thereof at 2. Within said chamber a plurality of collecting electrodes 3, consisting, for example, of metal plates, screens or the like, are supported in any suitable manner and are electrically grounded as indicated at 4 and also electrically connected in any suitable manner to the grounded side of any suitable source of high tension electric current. Between said collecting electrodes are provided suitable discharge electrode means indicated at 5, consisting, for example, of fine wires or rods of small diameter or other suitable members adapted to the production of silent or corona discharge therefrom when a suitable high electric potential is maintained between said discharge electrodes and the collecting electrodes. The discharge electrodes are shown as suspended from supporting rods 6, resting adjacent their ends on common supporting bars, one of which is shown at 7.

An insulator housing 11 is provided alongside the upper portion of the precipitator chamber, and the interior of said insulator housing is connected to the precipitator by means of a passage 12. The supporting bar 7 extends through passage 12 and rests on a supporting insulator 13. It will be understood, of course, that similar means are provided for supporting and insulating the

other end of the supporting bar 7 and also for supporting both ends of a similar bar extending parallel to the bar 7 and serving to support the other ends of the rods 6. A lead-in conductor 14 is connected to the supporting bar 7 and extends through the lead-in insulator 15 in the top wall of the insulator housing. Said conductor 14 may be connected to the high tension side of the source of high tension current.

Within the insulator housing 11 and surrounding the portions of the insulators 13 and 15 which are exposed to contact with gases passing from the precipitator chamber through the passage 12 into the space around said insulators, there is provided an inner casting 17. The outer housing 11 is shown as circular and the inner housing 17 as rectangular in cross section, so as to provide four compartments 18 between the walls of the inner and outer housings. Within these compartments are provided sources of radiant heat, shown as comprising incandescent electric lamps 19 connected to electric current supply wires 20. I have shown one of these incandescent lamps as located in each of the compartments 18 at the approximate level of the supporting insulator 13, and also one of such lamps located in each of said compartments at the approximate level of the exposed portion of the lead-in insulator 15. In order to permit radiation of heat from said sources of heat onto the surfaces of the insulators, heat transmitting wall portions or windows 21 are mounted between each lamp and the insulator which is to be heated thereby. These windows may be made of glass, quartz glass, or other suitable material adapted to permit free radiation of heat therethrough. Furthermore, in order to concentrate the heat from the lamps and cause the heat radiated therefrom to be directed principally toward the surfaces of the insulator, I may provide suitably curved mirrors or reflecting members 22 behind the respective lamps.

In the operation of the electrical precipitating apparatus it will be understood that the gas to be treated is passed through the precipitator chamber and between the discharge electrodes 5 and collecting electrodes 3 and that a high electric potential is maintained between said electrodes so as to cause electrical precipitation of suspended material contained in the gases, in the usual manner of such apparatus. A portion of the gas, however, will diffuse or circulate through the passage 12 into the space around the supporting insulator 13 and around the lower portion of the lead-in insulator 15. If the surfaces of said insulators which are thus exposed to the gases were not heated, water vapor or other condensable constituents contained in the gases would tend to condense upon contact with the relatively cool surfaces of said insulators and tend to cause

short circuiting and other disturbances as above described. However, with the electric lamps 19 burning, the heat produced thereby is radiated, with the aid of reflectors 22, 5 through the heat transmitting windows 21 and onto the surfaces of the insulators, thus keeping these surfaces at all times at a temperature sufficiently high to prevent any appreciable condensation or accumulation 10 thereon of condensable conducting materials contained in the gases.

It will be understood, of course, that the particular means shown in the drawings and described above are given by way of example only, and that many modifications may be made in the construction and arrangement 15 of the insulating means and of the means for heating the same by radiation.

I claim:

- 20 1. In combination with a high tension insulator, a casing surrounding and spaced from said insulator and having a portion formed of material adapted to transmit radiant heat, and heat radiating means positioned 25 at the opposite side of said casing from said insulator and adapted to cause radiation of heat through said heat transmitting portion of the casing onto the surface of said insulator.
- 30 2. In apparatus for electrical precipitation, the combination with a precipitator chamber, an insulator housing communicating with said chamber and having a portion thereof formed of material adapted to transmit radiant heat, a high tension conductor in said chamber and projecting into said housing, an insulator in said housing and providing a support for said high tension conductor, and means exterior to said chamber and housing 35 for radiating heat energy through the said portion of said housing to the surface of said insulator.
- 40

In testimony whereof I have hereunto subscribed my name this 3rd day of June, 1930.

45 HEINRICH BERNHARD RÜDER.
